INVENTOR

A. B. Auer.

ALBERT B. AUER, OF CHICAGO, ILLINOIS.

Letters Patent No. 91,198, dated June 15, 1869.

—
CHECK-BOOK CLIP.
—

The Schedule referred to in these Letters Patent and making part of the same.

To all whom it may concern:

Be it known that I, ALBERT B. AUER, of Chicago, in the county of Cook, and State of Illinois, have invented a new and useful Improved Device for Cutting Checks from Check-Books; and I do hereby declare the following to be a full, clear, and exact description of the same, reference being had to the accompanying drawings, and the letters and figures marked thereon, which form part of this specification, and in which—

Figure 1 represents a top or plan view of my invention applied to a check-book; and

Figure 2, an end view of the same; and

Figure 3, a top or plan view as applied to check-books with only one check on a leaf.

The nature of my invention consists in a simple straight-edge piece, with a suitable fastening, for fastening the same to a check-book, as hereafter more fully described.

To enable those skilled in the art to understand how to manufacture and use my invention, I will proceed to describe the same with particularity.

The same letters of reference refer to the corresponding parts in the different figures.

In the accompanying drawings—

A represents the check-book, and B, a sharp edged strip, or cutter, which extends across the checks in the check-book, and is fastened to the check-book by a spring-fastening, so that as each check is cut off, as hereafter described, the cutter will press upon the next

check, and so on till all the checks are taken from the book.

The cutter B is made as long as the width of the check-book, and it is secured to the check-book across the checks, at the place where it is desired to cut them, by means of a rubber spring, C, which is fastened to both ends of the cutter B, and passes beneath the checks, so as to hold the cutter B firmly upon the check.

When it is desired to cut a check, the person takes hold of the loose end of it, and raises it in such a way that the cutting-edge of the cutter B cuts it.

If there be more than one check on the same page in the check-book, I attach a sliding arm, or cutter, D, to the cutter B, in such a way that it can be moved thereon to the place where it is desired to cut the leaf of the check-book lengthwise. The cutter B will cut it across the check, and D, lengthwise of the book.

Having thus fully described the construction and operation of my invention,

What I claim, and desire to secure by Letters Patent, is—

The cutter B, with a suitable spring-fastening, for fastening the same to the check-book, when constructed and operating substantially as and for the purposes specified.
